H. B. KIMMEL

FIRE POT

Filed March 26, 1923

Inventor
Harry B. Kimmel

By, *Stuart C Barnes*
Attorney

UNITED STATES PATENT OFFICE.

HARRY B. KIMMEL, OF HIGHLAND PARK, MICHIGAN.

FIRE POT.

Application filed March 26, 1923. Serial No. 627,813.

To all whom it may concern:

Be it known that I, HARRY B. KIMMEL, a citizen of the United States, residing at 42 Gerald Ave., Highland Park, in the county 5 of Wayne and State of Michigan, have invented certain new and useful Improvements in Fire Pots, of which the following is a specification.

This invention relates to fire pots, and 10 more particularly to a device for protecting the burner in order to prevent the port opening becoming clogged with carbon deposits.

The object of my device is to provide an 15 easily operated device which can be actuated from outside the chimney. A further object is to so construct the device that it will be easily set into position and can be quickly and easily actuated so as to change the 20 position of the device when desired.

In the present form of fire pots, the burner is provided with a small opening in which the vaporized fuel is ejected. During the 25 priming operation, when the priming fluid is burning in the priming trough in order to heat the coils so that they will vaporize the fuel, this priming fuel burns with a yellow flame and a large amount of carbon is deposited on the burner. This often accumulates to such an extent that the port opening in the burner tube becomes clogged with the carbon deposits, and the port opening 30 must be cleaned before the fire pot can again be used. To clean this port opening it is necessary to remove the burner from the 35 chimney by unscrewing it from the preheating coils and withdrawing the same from out the chimney.

My device aims to overcome this difficulty 40 by protecting the port opening in the burner tube during the priming operation and my device can be withdrawn so as to open the port opening in the burner tube when the preheating tube has been raised to a sufficient 45 temperature to vaporize the fuel. At this time, the vapor under pressure is ejected through the port opening and burns with a blue flame, which of course, does not tend to form carbon in the port opening, as it is 50 the yellow flame which causes the carbon deposits to accumulate on the burner. In my device, the carbon deposits are accumulated 55 on the outside surface of the protecting sleeve and are not allowed to clog the port opening in the burner tube.

In the drawings:

Fig. 1 is an elevational view of a fire pot, partly in section and showing the protecting sleeve in place on the burner tube.

Fig. 2 is a detail in section showing the 60 protecting sleeve withdrawn.

Fig. 3 is a section on the line 3—3 of Fig. 1.

Fig. 4 is a detail in perspective of the 65 protecting sleeve.

The fire pot comprises a fuel oil reservoir *a*, a grid *b*, supported thereon, and a chimney *c* supported from the grid. The fuel is fed upwardly through the pipe connection *d* to which is connected the preheating coil *e*. The lower end of the preheating coil is provided with an elbow fitting *f*, in which the burner tube *g* is threaded. The chimney is provided with an opening *h* through which the burner tube projects, the 70 outer end of the tube being flattened as at *i*, so that it may be gripped by a wrench for screwing or unscrewing the burner into the elbow fitting *f*. The 75

The priming trough *j* is located near the 80 bottom of chimney. The said priming trough is adapted to hold a sufficient quantity of liquid fuel which is lighted to throw heat upwardly onto the preheating coil, in order to raise the temperature of the 85 preheating coil so that it will vaporize the fuel before it is ejected through the port opening *k* in the burner tube *g*.

In order to protect this burner opening *k*, which is a very fine pinhole drilled into the 90 burner tube, I provide a sleeve *m* which is slidably supported on the burner tube. This sleeve *m* is provided at its outer end with a downturned ear *n* which is positioned outside of the chimney as shown in Figs. 1 95 and 2. This downturned ear *n* acts as a handle by which the said sleeve may be slid along the burner tube. In Fig. 1, I show the sleeve *m* forced inwardly, the sleeve thereby extending over the port opening *k*. In Fig. 2, I show the sleeve *m* pulled outwardly to open the port opening *k* when it is desired to burn the vapor generated in the 100 preheating coil.

During the priming operation, the fuel 105 in the priming trough burns with a yellow flame, which tends to free the carbon from the fuel and to deposit the same on the burner. When the sleeve is in position as shown in Fig. 1, the carbon will be deposit- 110

- ed on the outside surface of the sleeve, thereby maintaining the port opening in the burner tube free from any carbon deposits. When the priming liquid has been burned 5 the sleeve may be withdrawn into the position as shown in Fig. 2, at which time the opening *k* is opened, and the generated vapor is ejected from the port opening and burns with a blue flame. Obviously, I have 10 provided a simple device by which the burner opening may be kept free of carbon accumulations, enabling the burner to always remain in a proper condition and not requiring the removal of the same in order to 15 clean the port opening as is necessary with the present fire pots.
- The sleeve *m* is provided with a projection *o*, that is bent slightly inwardly to bind the sleeve on the burner tube so it cannot slip 20 when in place.
- What I claim is:
1. In a fire pot, the combination of a chimney provided with a priming trough, a preheating tube suspended within the 25 chimney, a burner connected therewith and provided with a port through which the vapor generated in the preheating tube is ejected, and a guard movably supported by said burner and adapted to close said 30 port during the priming operation to maintain the port opening in the said burner free from carbon deposits.
  2. In a fire pot, the combination of a chimney provided with a priming trough, 35 a preheating tube suspended within the chimney, a burner tube connected therewith and provided with a port through which the vapor generated in the preheating tube is ejected, and a sleeve movably supported 40 on said burner tube and arranged to close said port opening during the priming operation to maintain the port opening in the said burner free from carbon deposits.
  3. In a fire pot, the combination of a 45 chimney provided with a priming trough, a preheating tube suspended within the chimney, a burner connected therewith and provided with a port through which the vapor generated in the preheating tube is ejected, and a guard slidably supported by 50 said burner and adapted to close said port during the priming operation to maintain the port opening in the said burner free from carbon deposits.
  4. In a fire pot, the combination of a 55
- chimney provided with a priming trough and an opening in the side thereof, a preheating tube suspended within the chimney, a burner tube connected therewith and projected through the said opening, and provided with a port through which the vapor generated in the preheating tube is ejected, and a sleeve slidably supported on the burner tube and adapted to close said port during the priming operation to maintain the 60 port opening in the burner tube free from carbon, said sleeve projected through the opening in said chimney whereby said sleeve may be actuated from the outside.
5. In a fire pot, the combination of a 70 chimney provided with a priming trough, a preheating tube suspended within the chimney a burner tube connected therewith and provided with a port through which the vapor generated in the preheating tube is 75 ejected, said burner tube projected through the walls of the chimney and flattened at the end thereof, and a sleeve provided with a downturned ear adapted to engage with the chimney wall to limit the inward movement of the sleeve whereby the sleeve when forced inwardly to the limit of its movement is adapted to close the port in the burner tube during the priming operation, to maintain the said port free from carbon. 80
6. In a fire pot, the combination of a chimney provided with a priming trough, a preheating tube suspended within the chimney, a burner connected therewith and provided with a port through which the vapor generated in the preheating tube is ejected, and a guard for closing said port during the priming operation to maintain the port opening in the said burner free from carbon deposits. 85
7. In a fire pot, the combination of a chimney provided with a priming trough, a preheating tube suspended within the chimney, a burner connected therewith and provided with a port through which the vapor generated in the preheating tube is ejected, and a guard for closing said port during the priming operation to maintain the port opening in the said burner free from carbon deposits, said guard projecting 95 through the walls of the chimney so that the same may be actuated from without the chimney.

In testimony whereof I affix my signature.

HARRY B. KIMMEL.
